Houston B. Marshall and Haskell L. Baker, Fort Worth, Tex., assignors to E. W. Gist, Oklahoma City, Okla.

Application November 26, 1948, Serial No. 149,816

Term of patent 14 years

(Cl. D31—4)

To all whom it may concern:

Be it known that we, Houston B. Marshall and Haskell L. Baker, citizens of the United States of America, residing at Fort Worth, in the county of Tarrant and State of Texas, have invented a new, original, and ornamental Design for a Fishing Lure, of which the following is a specification, reference being had to the accompanying drawing, forming part thereof.

We claim:

The ornamental design for a fishing lure, substantially as shown.

HOUSTON B. MARSHALL.
HASSELL L. BAKER.
